FIG. 1

FIG. 1 is a side elevational view of the sailing catamaran showing my design;

FIG. 2 is a top plan view of said sailing catamaran;

FIG. 3 is a bottom view of said sailing catamaran;

FIG. 4 is a front view of said sailing catamaran, the mast and sail being deleted in the interest of clarity;

FIG. 5 is a rear view of said sailing catamaran, mast, sail and rigging being deleted in the interest of clarity; and

FIG. 6 is a perspective view of said sailing catamaran as seen in the water, a portion of mast, sail and rigging being deleted in the interest of clarity.

This application is a continuation-in-part of application Ser. No. 320,622, filed Jan. 2, 1974, now abandoned.

I claim:

The ornamental design for a sailing catamaran, substantially as shown and described.
